UNITED STATES PATENT OFFICE.

JAMES WAYLAND, OF NEWARK, NEW JERSEY.

RAIL-JOINT.

SPECIFICATION forming part of Letters Patent No. 590,028, dated September 14, 1897.

Application filed May 29, 1897. Serial No. 638,689. (No model.)

To all whom it may concern:

Be it known that I, JAMES WAYLAND, a citizen of the United States, residing at Newark, county of Essex, State of New Jersey, have 5 invented certain new and useful Improvements in Rail-Joints, of which the following is a specification.

The object of my invention is to provide a mechanical connection between two adjacent 10 abutting rails of a railway-track without admitting of electrical connection between the same.

Devices having this general object in view 15 are sometimes provided with a bed-plate resting on adjacent cross-ties and serving as a support for the abutting rail ends, a strip of insulating material being interposed between at least one of the rail ends and the bed-plate. It has been found difficult to prevent 20 buckling or distortion of the bed-plate under the hammer-like blows it receives in service during the transit of rapidly-moving trains, which distortion permits the insulation to be destroyed by the grinding action of the rail 25 ends against the distorted bed-plate. My invention has in view particularly to provide against such a result, which, for example, in a signaling system might prove disastrous by creating false signals and jeopardizing the 30 safety of the passengers and trains.

In carrying out the invention I form the 35 plate with strengthening webs or ribs in such a manner as to permit an enormous strength to be attained with thicknesses of metal, preferably steel, which may be easily worked by dies and may therefore be produced at an expense far below what would be possible in ordinary plates of the same strength.

The several features of novelty will be hereinafter more fully described, and will be definitely indicated and ascertained in the claims appended to this specification.

In the accompanying drawings, Figure 1 is 45 a cross-section of a rail-joint embodying my invention, the plane of section being indicated by the line X Y of Fig. 3, looking in the direction of the arrow on said line. Fig. 2 is a similar cross-section on line X' Y', looking in the direction of the arrow on said line. Fig. 3 is a side elevation of a rail-joint embodying the invention. Fig. 4 is a perspective view of the improved bed-plate; and Fig. 5

is a plan of the insulating shim or plate used between the rail ends and the bed-plate.

Referring first to Fig. 4, I provide the bed-plate, which may be cast but is preferably punched from stout plate iron or steel, with 55 a vertical wall at one side formed by an upturned edge and a ridge at the opposite side composed of a double web, forming an arch of metal integral with the main body of the bed-plate. Both side walls are long enough to bridge adjoining cross-ties, thereby giving 60 the greatest rigidity against downward flexure and preventing any relative motion between the insulated rail ends and the bed-plate. At one end of the plate—that which supports the uninsulated rail end—I provide 65 a plurality of arched webs 3 3^a, integral with the body of the plate and having all around 70 their perimeters a flat web on a level with the main floor of the plate.

The construction will be readily understood 75 upon inspection of Figs. 1 and 4. It will be seen that between the arched webs and around the same the level of the plate has not been disturbed, so that when resting on the cross-tie there is no tendency for the edges of the raised parts to cut the fiber of the tie, and at 80 the same time an extraordinarily strong structure is made.

Slots 4 4^a are provided at one side of the 85 plate to permit bolts to pass through the same for the purpose of locking down the rail ends and the coupling-blocks and preventing outward spread of the rails. On the bed-plate when the joint is made is placed a shim or sheet of insulating material. (Shown in plan in Fig. 5.) It is provided with openings to surround the raised webs 3 3^a and permit it to 90 lie flat on the floor of the bed-plate. It is provided also with bolt-holes 5 5^a, adapted to register with holes 4 4^a when laid on the bed-plate.

The bed-plate in forming a rail-joint is laid 95 with the vertical wall 1 on the outside of the line of rails, and spikes are driven into the cross-ties, so that the heads overhang the walls of the notches 6 6^a and 7 7^a. The rail ends meeting between the cross-ties are preferably 100 separated by an insulating-strip 8 of indurated fiber or other tough material. The rail ends are prevented from spreading sidewise by coupling-blocks 9 9^a, of oak, set firmly be-

tween the head and base of the rails and extending down flush with the insulating-shim
 10. Horizontal bolts threading holes in the rails lock the coupling-blocks 9 9^a firmly
 5 to the rail ends, and iron washers or strips 12 prevent the bolts working into the wood
 10 of the blocks. Vertical bolts 13 bind the rail ends and coupling-blocks hard against
 15 the bed-plate and the insulating-shim, said
 10 bolts passing through the slots 4 4^a, which
 15 permit the rails to shift under expansion and
 20 contraction, due to changes of atmospheric
 25 temperature, without shifting the road-bed or
 30 bed-plate.

15 It will thus be seen that all parts of the
 20 joint are firmly locked together and there is
 25 a minimum possibility for any of the parts
 30 to shift their positions, and even if the insu-
 lating-shim should crack or break under the
 35 strains to which the joint may be subjected
 40 it cannot be displaced so as to permit contact
 45 of the insulated rail end with the bed-plate
 50 or any other part which might establish elec-
 55 tric communication between the two rail
 60 ends. The repair of a joint having a dam-
 65 aged shim is an operation of great simplicity
 70 in my organization, the vertical bolts being
 75 loosened and the rails raised to permit with-
 80 drawal of the old shim and the insertion of a
 85 new one.

It will be seen that the block 9 may be
 25 easily slid away from the joint without the
 30 slightest disturbance of the block 9^a, its bot-
 35 tom surface being on the plane of the top of
 40 the arched rib 2 and resting on the rib and
 45 the shim whose top surface is also in the
 50 plane of the top of rib 2.

It will be noted that the shim completely
 20 surrounds one of the arched webs on the end
 25 of the bed-plate. This construction prevents
 30 it from shifting lengthwise of the track.

Having thus described my invention, what
 I claim as new, and desire to secure by Letters
 Patent, is—

45 1. A bed-plate for a rail-joint provided with
 50 upturned integral webs at the sides, one of
 55 said webs having a double wall upset from
 60 the body of the plate and surrounded by the
 65 floor of the plate at one side and both ends,
 70 for the purpose described.

2. A bed-plate for a rail-joint provided with
 25 a strengthening side rib integral with the body
 30 of the plate formed of an arched web having
 35 double walls upset from the body of the plate

and surrounded by the floor of the plate at 55
 one side and both ends.

3. A bed-plate for a rail-joint provided at
 20 one end with an arched web to form a support
 25 for the uninsulated rail end, said web being
 30 integral with the floor of the plate and sur-
 35 rounded by the same on all sides of its periph-
 40 ery.

4. A bed-plate for a rail-joint provided at
 25 one end with a plurality of arched webs to
 30 form a support for the uninsulated rail end, 65
 35 said webs being integral with the floor of the
 40 plate and surrounded by the same on all sides
 45 of their peripheries.

5. A bed-plate for a rail-joint provided at
 30 one end with a plurality of arched webs to 70
 35 form a support for the uninsulated rail end,
 40 said webs having between them a body of
 45 metal lying in the same plane as the floor of
 50 the plate.

6. A bed-plate for a rail-joint provided with 75
 35 upturned integral webs at its sides to lock the
 40 rail ends against lateral motion, and having
 45 at one end an arched web to support the un-
 50 insulated rail end, said web being integral
 55 with the floor of the plate and surrounded by
 60 the same on all sides of its periphery.

7. A rail-joint comprising coupling-blocks
 40 connecting the rail ends and a bed-plate bolted
 45 thereto spanning two cross-ties and having in-
 50 tegral upturned side webs, one of which has 85
 55 double walls.

8. A rail-joint comprising coupling-blocks
 45 connecting the rail ends, and a bed-plate bolted
 50 thereto spanning two cross-ties, and having
 55 integral upturned side webs and an arched 90
 60 web at one end rising above the floor of the
 65 plate to form a seat for one rail end, and a
 70 shim of insulating material completely sur-
 75 rounding said arched web and supporting the
 80 insulated rail end. 95

9. A rail-joint comprising a bed-plate hav-
 40 ing a side strengthening-rib, a shim whose top
 45 surface is flush with the top of the rib, and a
 50 removable coupling-block bearing on the shim
 55 and rib. 100

In testimony whereof I have hereunto sub-
 45 scribed my name this 27th day of May, A. D.
 50 1897.

JAMES WAYLAND.
